CARTRIDGE EXTRACTORS

Rowland J. Kopf, Rocky River, Ohio, assignor, by mesne assignments, to Olin Mathieson Chemical Corporation, a corporation of Virginia

Application April 16, 1954, Serial No. 423,650

7 Claims. (Cl. 42—25)

This invention relates generally to cartridge extractors and is directed more specifically to the provision of an improved claw extractor.

In powder-actuated tools, the explosive energy of a blank cartridge is used to operate the tool, a common application being that of driving a fastener. Although conventional cartridges are employed, frequently the breech pressures are extremely high and, indeed, approach values that would be regarded as "proof loads" for firearms. Under such conditions, considerable difficulty is encountered in providing for reliable extraction.

In many applications, it is desirable to use a claw extractor, one reason being that this type of extractor is adapted for bolt actions, which inherently possess high strength. Heretofore, such claw extractors have been simple, resilient members or pivoted members spring-biased inwardly, the bias being relied upon to hold the claw in engagement with the rim of the case. If the cartridge case does not slide readily from the chamber, however, this bias may be inadequate to prevent the claw from pulling over the rim of the case.

Accordingly, it is an object of the invention to provide improved extracting mechanism of simple, inexpensive, but rugged, construction for powder-actuated tools and other apparatus utilizing high-powered cartridges. Among the more specific objects of the invention will be noted the provision of an extractor that is readily assembled and replaced; the provision of an extractor that automatically engages behind the rim of a cartridge upon closure of the breech; and the provision of an extractor that is positively locked to the cartridge rim during opening of the breech.

Briefly, the extractor herein disclosed is adapted to be mounted upon a breech block or bolt which is opened axially. The extractor is a rigid, floating member carried on the bolt and mounted for relative movement axially between predetermined advanced and retracted positions. While the extractor is radially displaceable and includes a claw which rides over and engages behind the rim of the case upon forward movement of the bolt and extractor, such radial displacement is permitted only when the extractor is in its retracted position. The bolt includes an outer ledge cooperating with the front portion of the extractor to lock it against radial displacement when in advanced position relative to the bolt. Otherwise, the bolt may carry an encircling spring element which engages the outer face of the extractor, thereby to permit lateral displacement of the extractor as the claw rides over the rim of the case and to force the claw into locking engagement with the rim as the breech is closed with the extractor in its retracted position. The tail or rear portion of the extractor is shaped to permit such tipping or radial displacement of the claw when the extractor is in its retracted position relative to the bolt.

Other features of the invention will be in part apparent from and in part pointed out in the following de-

2

tail description taken in connection with the accompanying drawings, in which:

Fig. 1 is a sectional view illustrating parts of a powder-actuated tool embodying this invention, the breech being open;

Fig. 2 is an oblique detail view, portions of the bolt being cut away to expose the breech of the barrel;

Fig. 3 is a view similar to that of Fig. 1, but showing the positions of parts as the breech is closed;

Fig. 4 is a view similar to that of Fig. 1, but with the breech closed;

Fig. 5 is a view similar to that of Fig. 1, showing positions of parts as the breech is opened; and

Fig. 6 is a view similar to that of Fig. 2, illustrating an alternative embodiment of the invention.

As an exemplary application of the invention, in Fig. 1 there is shown a powder-actuated tool used to drive a fastening element 1 into material, such as concrete, which is otherwise difficult to penetrate. A barrel assembly 3 and a receiver assembly generally designated 5 are arranged to be broken for breech loading. In the barrel assembly 3, there is a barrel 7 which is mounted for axial movement within a housing 9. A breech block or bolt 11 is mounted within a receiver 13, and the bolt is recessed or counterbored at 15 to receive the breech of the barrel in telescoping relationship after insertion of a cartridge 17.

Fig. 1 illustrates an unlocked breech type of construction, but it should be understood that safety devices could be provided to prevent the tool from being fired with the breech open. For example, in the copending application Serial No. 335,034, filed May 14, 1953, and now abandoned, of which I am a joint inventor, there is disclosed mechanism which prevents the tool from being fired without first pressing the muzzle 19 of the barrel against the work surface. When pressure is applied to the tool, the barrel 7 is moved rearwardly within its housing 9 into closing engagement with the bolt 11, the bolt 11 then being carried back to release the safety and arm the tool. The details of such safety mechanism do not form a part of this invention, hence are not disclosed.

In the above-mentioned application, a removable breech plug is recessed within the barrel to hold the cartridge case. After firing, this plug is removed from the barrel and pressed over a stud to eject the spent shell. In reloading, the plug is reinserted and a cartridge loaded, but such extracting and loading procedures are necessarily time-consuming, hence the desirability of providing an extractor. Extractors as heretofore known, however, are not suited for the heavy service to which a powder-actuated tool is put.

The mechanism disclosed herein includes a rigid claw extractor element 21, which floats within a recess 23 milled in the outer portion of the bolt. The front wall 25 of this recess is located back from the front 27 of the bolt but is located forwardly of the bottom 29 of the counterbore 15, an opening thus being provided into the counterbore. A claw 31 formed at the forward end of the extractor enters the counterbore through this opening, and a recess 33 is milled in the breech of the barrel 7 to accommodate the claw 31 when the breech is closed. This claw is rounded to ride over and engage behind the rim of the case as the breech is closed.

As shown in Fig. 1, the extractor 21 is of a longitudinal dimension slightly less than that of the recess 23, and tapers in a forward direction. At its forward end above the claw 31, a shoulder 35 is formed in alignment with the wall of the counterbore 15 so that the extractor is movable relative to the bolt between advanced and retracted positions. In its retracted position, the extractor is radially displaceable as the claw rides over the rim

of the case; and in its advanced position, the shoulder 35 locks under the shoulder 25 of the bolt, thereby preventing radial displacement of the claw.

Movement between advanced and retracted positions is limited by engagement of the extractor 21 with the front and rear walls of the recess 23. The tail or rear portion 36 of the extractor is canted, however, so that the extractor may tip or pivot back as the claw rides over the rim of the case. It is also desirable to provide extractor biasing means in the form of a split ring 39, which is recessed within a groove 37 encircling the bolt. This ring engages the outer face 41 of the extractor so that the extractor is biased inwardly and will engage behind the rim of the case as the bolt is closed. In closing the bolt, the extractor is forced rearwardly to its retracted position by initial engagement with the cartridge case, and the spring member 39 yields to permit the claw 31 to ride over the rim.

The outer face 41 of the extractor may be tapered forwardly, as illustrated, so as to develop a wedging cooperation with the spring element 39, which also limits forward movement of the extractor within its recess and to some extent prevents radial displacement of the extractor when in its advanced position.

In operation, the cartridge 17 is loaded with the tool broken. The receiver barrel assembly 2 is then swung into alignment with the receiver assembly 5 and connected thereto by suitable means (not shown), so that the barrel 7 is aligned with the counterbore 15 of the bolt. When pressure is then applied to the muzzle 19 of the barrel, the breech portion of the barrel telescopes within the counterbore 15 to close the breech. As the breech is closed, the extractor is moved to its retracted position and rides over the rim of the case, as shown in Fig. 3. When the breech is closed and the tool armed, the extractor is engaged behind the rim of the case, as shown in Fig. 4.

Subsequently, as the breech is opened, the extractor is moved to its advanced position by the inherent resistance of the case to extraction (Fig. 5). In moving to its advanced position, the shoulder 35 of the extractor engages beneath the inner wall of the bolt and the extractor becomes positively locked against radial displacement. Being locked, the claw cannot slip over the rim should the case tend to stick in the chamber.

In the embodiment of Figs. 1-5, the recess 33 in the barrel would be maintained in alignment with the extractor, as by splines (not shown). In some instances, it may be desirable to provide for a locked breech type of construction. Referring to Fig. 6, the barrel is provided with locking lugs 51, which engage with similar lugs 53 on the bolt upon relative rotation. In this instance, however, provision must be made for rotary movement of the extractor relative to the bolt or barrel. To that end, either the recess 33 in the barrel may be widened, as shown in Fig. 6, or the recess 23 in the bolt may be widened in a similar manner, so that the extractor may move radially. Also, instead of the tail 136 of the extractor being canted, the back 138 of the recess 35 may slope rearwardly as shown in Fig. 6.

From the foregoing, it will be apparent that the extractor disclosed provides for a positive locking engagement with the rim of a cartridge, yet the structure is simple in construction and troublefree in operation. Although several embodiments have been disclosed in detail, it is to be understood that the invention is not limited thereto, but the drawings and description thereof are to be understood as being merely illustrative. It is realized that many modifications and variations will present themselves to those skilled in the art without departing from the spirit of this invention or the scope thereof as set forth in the appended claims.

Having thus described the invention, what is claimed and desired to be secured by Letters Patent is:

1. In cartridge-firing apparatus having a barrel for re-

ceiving a cartridge, a breech block mounted for axial movement relative to the barrel, and an extractor carried by the breech block; the improvement that comprises said extractor being guided for movement relative to the breech block in a direction parallel to the axis of the barrel, a first stop formed on the breech block to limit rearward movement of the extractor relative to the breech block, said extractor having a forwardly-disposed claw shaped to ride over the rim of a cartridge with the extractor engaged against said first stop as the breech is closed, spring means for biasing the claw radially inward into gripping engagement with the rim, a second stop formed on the breech block to limit forward movement of the extractor relative to the breech lock, and said breech block being formed with inwardly-facing shoulder means which locks the claw of the extractor in gripping engagement with the rim only when the extractor is engaged against said second stop, said extractor being movable from the first to the second stop with the claw in gripping engagement with the rim.

2. In cartridge-firing apparatus having a barrel for receiving a cartridge, a breech block mounted for axial movement relative to the barrel, and an extractor carried by the breech block; the improvement that comprises said breech block being formed with a guide slot, said extractor being received in said slot for movement in a direction parallel to the axis of the barrel between front and rear positions relative to the breech block, said slot terminating in a rear stop having a pivotal cooperation with the tail of the extractor, said extractor having an integral forwardly-disposed claw shaped to ride over the rim of a cartridge with the tail of the extractor engaged against said rear stop as the breech is closed, spring means biasing the claw portion of the extractor radially inward into gripping engagement with the rim, said guide slot in part terminating in a forward stop cooperable with the extractor and being formed with an inwardly-facing shoulder cooperable with a part of the extractor when the extractor is in its front position said shoulder being adapted to lock the claw in gripping engagement with the rim only when the extractor is in its front position, said extractor being movable in its guide slot from the rear to the forward stop with the claw in gripping engagement with the rim.

3. Apparatus as set forth in claim 2, wherein the breech block is counterbored to receive the breech end of the barrel in telescoping relationship, said guide slot in the breech block opening inwardly into the counterbore to admit the claw of the extractor and otherwise being closed by a rearwardly-facing shoulder disposed between the base of the counterbore and the front of the breech block.

4. Apparatus as set forth in claim 2, wherein the extractor is biased inwardly by a resilient ring of substantial thickness encircling the breech block and in part engaging said extractor.

5. Apparatus as set forth in claim 4, wherein the outer face of said extractor tapers inwardly in a forward direction, thereby to develop a wedging cooperation with said ring upon forward movement of the extractor relative to the breech block.

6. Apparatus as set forth in claim 5, wherein said ring is recessed within a groove encircling the breech block, said breech block being contained in an encircling housing which limits outward displacement of said ring.

7. Apparatus as set forth in claim 2, wherein said slot terminates in a back wall forming said rear stop, said back wall and the tail portion of said extractor being substantially divergent from one another in an outward direction, thereby to permit said extractor to tip backwardly within said slot as the claw rides over the rim of the cartridge case.
